Primary Examiner — Shannon Weekley Morgan*Assistant Examiner* — Clare A Gannon(74) *Attorney, Agent, or Firm* — Klein, O'Neill & Singh, LLP(57) **CLAIM**

The ornamental design for a roller blind, as shown.

DESCRIPTION

FIG. 1 is a perspective view, taken from the front and left side, of a roller blind, in accordance with our new design; FIG. 2 is a front elevation view of the roller blind shown in FIG. 1;

FIG. 3 is a rear elevation view of the roller blind shown in FIG. 1;

FIG. 4 is a side elevation view of the roller blind shown in FIG. 1, taken from the left side of FIG. 1;

FIG. 5 is a side elevation view of the roller blind shown in FIG. 1, taken from the right side of FIG. 1;

FIG. 6 is a top plan view of the roller blind shown in FIG. 1; and,

FIG. 7 is a bottom plan view of the roller blind shown in FIG. 1.

1 Claim, 5 Drawing Sheets(56)
